UNITED STATES PATENT OFFICE.

JOHN H. NEVILLE, OF WALVILLE, WASHINGTON.

GAME.

1,372,770.

Specification of Letters Patent. Patented Mar. 29, 1921.

Application filed January 12, 1920. Serial No. 351,045.

To all whom it may concern:

Be it known that I, JOHN H. NEVILLE, a citizen of the United States, residing at Walville, in the county of Lewis and State 5 of Washington, have invented a certain new and useful Improvement in Games, of which the following is a specification.

My invention relates to improvements in games in which rings are thrown at pegs in 10 an attempt to ring the same and the object of my invention is to provide a novel peg and ring game that is interesting and mathematically instructive and that affords an opportunity for the cultivation and display 15 of considerable skill and dexterity.

Another object is to provide a game in which the ringing of various pegs is likened unto the ringing or calling of various telephone stations on lines of telephone systems 20 and one in which the apparatus on which the game is played is made to represent the top end of a telephone pole with its cross-arms, pins and insulators, the pins and insulators serving as pegs at which the rings 25 may be thrown.

A further object is to provide an apparatus that is relatively cheap and simple in its plan of construction and that is made in several parts which may be packed in a relatively small package and which are interesting for children to assemble. 30

I accomplish these objects by devices illustrated in the accompanying drawings, wherein—

Figure 1 is a view in front elevation of the apparatus on which the game is played;

Fig. 2 is a view in side elevation of the same; and

Fig. 3 is a plan view of one of the rings 40 used in playing the game.

Referring to the drawings, throughout which like reference numerals indicate like parts, the numeral 5 designates a vertical post that is supported in an upright position by two base members 6 and 7 that are disposed at right angles to each other; the base member 6 having a block 10 crosswise thereof and rigidly secured thereto by nails or screws 8 as shown by dotted lines in Fig. 45 1; and the upright post 5 is adapted to be inserted between the base member 7 and the block 10 so that its bottom end rests upon the base member 6; and two cross-bars 11 and 12 that are rigidly secured to the edges

of the post 5 and rest upon the top edges of 55 the base member 7 and block 10. The post 5 is secured to the base structure by a bolt 13 that passes through the base member 7, the bottom of the post 5 and the block 10. The cross-bars 11 and 12 brace the post 5 60 and make it more rigid.

The post 5 is provided near its top end with a rigidly secured transverse block 14 upon which rests a crossarm 15 that is provided near its outer ends with rigid upright 65 pins 16 and 17 to the top ends of which are attached blocks 16' and 17' respectively that are shaped to look like glass insulators to which the telephone wires are secured when they are seen in front or rear elevation. 70 The crossarm 15 is secured to the post 5 by a bolt 18.

Disposed about half way between the block 14 and the base of the apparatus is another transversely arranged rigid block 75 20 upon which rests a crossarm 21 that is secured to the post 5 by a bolt 22 and is provided with four upright pins 23, 24, 25 and 26 that are arranged in spaced apart relation two on each side of the post 5 and that have 80 blocks 23', 24', 25' and 26' that represent telephone insulators secured thereto.

The cross-arm 21 is braced by angular brace-arms 27 and 28 that are secured to the crossarm 21 by bolts 30 and that have 85 their bottom ends secured on the bolt 13.

From the above description it will be understood that the apparatus described can be packed in a relatively small compact space before it is set up and it will be seen 90 that the same, while it is not difficult to erect will nevertheless afford an interesting problem for the children.

The rings 31 with which the game is played may be made of wire with the ends 95 twisted together as at 32 shown in Fig. 3.

Each pin will be designated by the name of a city and by a charge of an amount of money as shown in Fig. 1.

In playing the game each player will start 100 with six rings which represent a day's toll service. Six days' toll service, or thirty-six rings, constitute a week's toll service, and the total charges for the week's toll service constitute a complete game; the object of 105 such game being to have the least amount of money charged against one at the end of play. The player must select a certain

pin or call before he begins to throw his six rings and if he rings the selected call or pin the cost of such call is charged to his account; but if fails to ring the call or 5 pin selected by him, he is penalized a certain amount of money which is added to his account. If he rings the selected call before all of his six rings are thrown he may put in what may be known as "collect calls" 10 which means that he may select and throw at other pins or calls and if he rings the same the amounts of money designated by these calls are charged to his opponent's account. An unsuccessful attempt to ring a 15 station is known as "they don't answer," and for six such plays a "service charge" or penalty of two dollars is made.

If the amounts represented by the several pins are one, three and five dollars as shown 20 in Fig. 1, and the penalty for not ringing the pin selected is two dollars, then the lowest charge that a player can have after throwing six rings and only getting his call will be one dollar. If he elects to ring either 25 Chicago or New York and succeeds in doing so before his rings are all used he then has the privilege of putting in a "collect call" for another city, as Seattle or San Francisco, and if he is successful in ringing the call 30 elected the cost of such call is charged to his opponent's account. If a player accidentally rings a call not elected he is said to get "the wrong number" and he is penalized the amount of two dollars; and if after selecting a call he rings such call and then 35 he plays for a "collect call" and in throwing for such call he again rings his first named

call, the play is known as "the line is busy" and the player is penalized two dollars.

The above game is interesting, affords an 40 opportunity for the development and display of skill in throwing the rings and also affords beneficial practice in mathematics, especially for the children, in keeping an account of and totaling the amount of 45 charges.

It will be understood that changes in the form of the apparatus and changes in the method of playing the game may be resorted to without departing from the spirit of my 50 invention.

What I claim is:

A telephone game apparatus comprising a base formed of two members arranged at right angles to each other, an upright support removably secured to said base, two cleats secured on the front side of said upright support in spaced apart relation, a crossarm supported on said uppermost cleat, a bolt securing said crossarm to said upright support, an upwardly projecting peg near each end of said crossarm, another crossarm supported on said lowermost cleat, a bolt securing said lowermost cross arm to said upright support, two upwardly projecting pegs secured to said lowermost crossarm on each side of said upright support, brace members supporting said lowermost crossarm, and rings adapted to be thrown over said pegs.

In witness whereof, I hereunto subscribe my name this 31st day of December, A. D. 1919.

JOHN H. NEVILLE.
